UNITED STATES PATENT OFFICE.

EZEKIEL J. WILSON, OF EAST GREENBUSH, NEW YORK, ASSIGNOR TO F. C. HUYCK & SONS, OF RENSSELAER, NEW YORK, A CORPORATION OF NEW YORK.

PAPER-MAKING MACHINE.

Application filed December 2, 1922. Serial No. 604,495.

To all whom it may concern:

Be it known that I, EZEKIEL J. WILSON, a citizen of the United States, residing at East Greenbush, in the county of Rensselaer 5 and State of New York, have invented certain new and useful Improvements in Paper-Making Machines; and I do hereby declare the following to be a full, clear, and exact description of the invention, such as will 10 enable others skilled in the art to which it appertains to make and use the same.

The invention relates to paper making machines.

In these machines portions of the moisture in the web of paper stock formed on the Fourdrinier wire are successively removed by the felt jacketed couch roll at the delivery end of the wire and by the pressure rolls and felts of the series of presses 20 through which the web passes on its way to the heated calender rolls which complete the drying and finishing of the web. To secure the most efficient operation of 25 the machine the couch roll and the pressure rolls of the presses should apply as heavy a pressure to the paper stock as is permissible without crushing or injuring the fibres of the stock so that each will remove the maximum amount of moisture and thus reduce the amount which must be subsequently removed by the more expensive operation of the heated dryer. The efficient operation of the couch roll and of the pressure rolls also requires that any pressure applied to a roll shall be applied equally at 30 both ends so that the web of stock will be subjected to a uniform pressure throughout its width by each of the rolls. It has been found, however, that with the constructions 35 heretofore in use there is a wide variation in the pressure applied by a roll under a given adjustment of the means for pressing the roll against the web and that there is also a wide variation in the pressures applied by the opposite ends of the roll even 40 when the means for forcing the roll against the web is apparently adjusted to secure the same pressure at each end of the roll.

It is the object of the present invention 45 to provide means by which pre-determined pressure may be uniformly applied throughout the width of the web of paper stock by any or all of the rolls applying pressure thereto so that the proper adjustments may 50 be made to secure the most efficient operation

of the machine. A further object of the invention is to provide means by which the pressure or pressure being applied to the web during its passage through the machine may be indicated or indicated and recorded 60 at points where they may be conveniently observed and inspected.

To these ends one feature of the invention contemplates the application to each end of one or more of the rolls which press upon the web of stock, of a spring link through which pressure is applied to the roll, and the provision of mechanism operated by the resulting deflection or distortion of the link to indicate or indicate and 70 record the pressure transmitted therethrough to the corresponding end of the roll. This enables the proper adjustments to be made in the means for applying pressure to the opposite ends of the roll to 75 secure that pressure which will give the most efficient results and also to secure the same pressure at each end of the roll. The application of this feature of the invention to each of the rolls which apply pressure to 80 the web also enables the proper adjustments to be made to secure that relation between the successive pressing operations which may be found to give the most efficient results. 85

To enable the convenient observation of the pressures being applied at the various ends of the rolls and thus avoid the additional attention and the probable neglect on the part of the operator, which would 90 result from locating the pressure indicating devices at or adjacent to the ends of the rolls, a further feature of the invention contemplates the provision of means for indicating or indicating and recording the 95 pressure applied to each end of a roll at any desired point or points however remote from the roll. The indicating devices may thus be located where the operator may readily and conveniently inspect them to determine 100 whether the proper pressures are being applied and to determine what adjustments should be made to correct any indicated variations from normal. The superintendent 105 may also conveniently observe whether the machine is being properly run by the operator. In case recording indicators are utilized the record of the pressures applied by the various rolls serves also as a check on the operator which indicates any neglect 110

to make the adjustments requisite for the most efficient operation of the machine and thus reduces the chances of such neglect or its continuance for any length of time.

6 The invention will be readily understood from the accompanying drawings in which Fig. 1 illustrates diagrammatically the application of the preferred form of the invention to a Fourdrinier paper machine, 10 Fig. 2 is a detailed end elevation of one of the pressure applying rolls, Fig. 3 is an elevation looking toward the left in Fig. 2, and Fig. 4 is a diagrammatic detail of one of the indicating and recording devices.

15 In Fig. 1 the Fourdrinier wire upon which the paper stock is formed into a web is indicated at 2, the lower couch roll about which the wire passes is indicated at 4 and the upper felt jacketed couch roll which 20 removes a part of the moisture and presses the stock into compact web form is indicated at 6. The continuous web of paper stock S formed on the wire passes from the couch rolls through a series of presses 25 in each of which a further portion of the moisture is removed by a pressure roll 8 and felt 10. From the last press the partially dried web of stock passes to the heated calender rolls of the dryer which completes 30 the drying and finishing of the web. Each of the pressure applying rolls, including the couch roll 6, is so mounted that it may be pressed against the web passing beneath it, and adjustable means is provided at each 35 end of each roll for pressing that end of the roll against the web. As shown each end of each roll is journaled in a pivoted carrier 12 and is forced against the web by a weight 14 adjustably secured on one 40 of two compound levers 16, 18, the other one of which is connected with the carrier by a link 20.

In order that the pressure applied to the 45 end of the roll by the weight and compound levers may be measured and indicated in a uniformly accurate and reliable manner the link through which the pressure is transmitted to the end of the roll is a spring link connected to operate an indicating 50 mechanism through the distortion or deflection due to such pressure. As shown the spring link comprises an elliptical spring 22, one end of which is connected by a hook 24 with the roll carrier 12, and the other end 55 of which is connected by an adjustable hook 26 with the lever 18. A variation in the pressure transmitted through the link 22 will result in a movement of the sides of the link toward or away from each other 60 which is proportional to such variation. This movement is utilized to operate an indicating mechanism which, so far as certain features of the invention are concerned, may be of any suitable construction such 65 for instance as a scale and finger mounted

on the link, but which is preferably so constructed and operated that its indicating devices may be located at any desired point however remote from the end of the roll. As shown the means for indicating the pressure transmitted through the link 22 comprises an electric circuit including two synchronized magnetic fields 28 and 30 within which are arranged two similar armatures 32 and 34. The field 28 is mounted on a 70 plate 36 secured to one side of the spring link 22, while its armature 32 is mounted on the plate to rotate within the field, and its position is determined by a rack 38 secured to the other side of the link and engaging a pinion on the pivot of the armature. Movement of the sides of the link toward or from each other will result in a 75 rotation of the armature within the magnetic field and the position of the armature within the field will depend upon the relation of the two sides of the link to each other and therefore to the pressure being transmitted through the link to the end of the roll. The other magnetic field 30 and 80 armature 34 are connected with indicating devices which may be arranged at any desired point in the electric circuit and are preferably constructed to record as well as indicate the pressure transmitted through 85 the link 22 to the end of the roll. As indicated diagrammatically in Fig. 4 the magnetic field 30 may be mounted in fixed position while the armature 34 is mounted to rotate within the field and is provided at 90 its axis with a pinion 40 engaging a segment 42 secured to the pivot 44 of an indicating and recording finger 46. The end of the finger may be arranged to play over a scale calibrated to indicate in pounds the 95 pressure transmitted through the link 22 and this scale may be formed on a time chart 48 operated by clock mechanism as is usual in recording indicators. The coils of the synchronized magnetic fields are so 100 wound and arranged that movement of the armature 32 will be accompanied by a corresponding movement of the armature 34 and consequently the position of the armature 34 and the indicating and recording 105 finger 46 will depend upon the position of the armature 28 and therefore upon the pressure being transmitted through the spring link 22 to the end of the pressure roll.

The indicating recorders may be located wherever found most convenient and if desired additional recorders may be included in series in each circuit to indicate, for instance, in the superintendent's office the 110 pressures being applied by the rolls of the various machines in the plant.

While it is preferred to employ substantially the construction and arrangement shown and described it will be understood 115

that this construction and arrangement is not essential to the broader features of the invention and may be varied or modified as found desirable or best suited to the conditions under which the invention is to be utilized.

What is claimed is:

1. A paper making machine having, in combination a roll for applying pressure to the moist web of stock passing through the machine, means for applying an adjustable pressure to each end of the roll including a spring link through which the pressure is applied, and a pressure indicating mechanism corresponding to each link operated by the distortion of the link.
2. A paper making machine having, in combination, a roll for applying pressure to the moist web of stock passing through the machine, a roll carrier at each end of the roll, a spring link connected to each carrier, means for transmitting an adjustable pressure to the carrier through the link, and a pressure indicating mechanism operated by the distortion of the link.
3. A paper making machine having, in combination, a series of rolls for successively applying pressure to the moist web of stock passing through the machine, means for applying an adjustable pressure to each end of each roll including a spring link through which the pressure is applied, and a pressure indicating mechanism corresponding to each link operated by the distortion of the link.
4. A paper making machine having, in combination, a roll for applying pressure to the moist web of stock passing through the machine, means for applying an adjustable pressure to each end of the roll, and mechanism for indicating at a point remote from the pressure applying means the pressure applied to the roll thereby.

5. A paper making machine having, in combination, a roll for applying pressure to the moist web of stock passing through the machine, means for applying an adjustable pressure to each end of the roll, including a spring link through which the pres-

sure is applied, two synchronized magnetic fields with armatures therein corresponding to each link, one field and armature being connected to be relatively moved by distortion of the link, and indicating devices connected to be operated by the accompanying relative movement of the other field and armature.

6. A paper making machine having, in combination, a series of rolls for successively applying pressure to the moist web of stock passing through the machine, mechanism for applying an adjustable pressure to each end of each roll, including a spring link through which the pressure is applied, two synchronized magnetic fields with armatures therein corresponding to each link, one field and armature being connected to be relatively moved by distortion of the link, and indicating devices connected to be operated by the accompanying relative movement of the other field and armature.

7. A paper making machine having, in combination, a roll for applying pressure to the moist web of stock passing through the machine, means for applying an adjustable pressure to each end of the roll, and means for recording the pressure applied to each end of the roll during the operation of the machine.

8. A paper making machine having, in combination, a roll for applying pressure to the moist web of stock passing through the machine, means for applying an adjustable pressure to each end of the roll including a spring link through which the pressure is applied, and a pressure recording mechanism corresponding to each link operated by the distortion of the link.

9. A paper making machine having, in combination, a roll for applying pressure to the moist web of stock passing through the machine, means for applying an adjustable pressure to each end of the roll, and mechanism for recording at a point remote from the pressure applying means the pressure applied by the roll thereby.

EZEKIEL J. WILSON.
